UNITED STATES PATENT OFFICE.

JOHN HAYS HAMMOND, JR., OF GLOUCESTER, MASSACHUSETTS.

MODULATING REFLECTOR ADJUSTABLE AS TO NORMAL POSITION.

Application filed December 8, 1925. Serial No. 74,054.

This invention relates to improvements in stringed musical instruments, and more particularly to means for modifying and modulating the sound produced thereby.

5 The present invention features a sound modulator adapted particularly for a piano, including mechanism adjustable in accordance with variations in the brilliancy of tuning of the individual instrument to which the 10 device may be applied.

This application is an improvement over application Serial No. 753,558, filed by me December 3rd, 1924.

I have found experimentally that when the 15 modulating device shown and described in the said prior application is entirely closed, many of the harmonics of the music are suppressed. The quality of the sound emitted from the instrument is greatly changed, the sound seeming to be deadened or dull. It appears from 20 my experiments, that the production of harmonics is an important factor in the determination of the quality of sound emitted from a particular instrument and in the effectiveness or "brilliance" of tone. It is desirable 25 that such brilliance be enhanced, if agreeable musical effects are to be produced.

Accordingly, it is one object of the present 30 invention to provide a modulating means which may be adjusted into predetermined position in accordance with the characteristics of the instrument so as to enhance the brilliance.

Another feature of the invention relates to 35 the provision of means whereby abrupt deadening of the sound is effectively avoided, thus producing more agreeable changes in expression in the music, and improving the control of expression.

40 Another feature relates to the provision of an indicating device for indicating the extent of normal movement of the sound modulating means.

Other objects will appear from the following 45 description taken in connection with the accompanying drawings, in which

Figure 1 is a front elevation, with parts broken away, of an instrument embodying features of the invention;

50 Figure 2 is a horizontal section taken on the line 2-2 of Figure 1;

Figure 3 is a section of an enlarged detail

of the mechanism taken on the line 2-2 of Figure 1; and

Figure 4 is an enlarged detail in elevation 55 of part of the mechanism shown in Figure 1 and is shown in operation in relation to Figure 3, both figures showing the mechanism in the normal position.

Figures 5 and 6 are the same as Figures 3 60 and 4, but with the mechanism in a partly closed position.

Figures 7 and 8 are similar to Figures 3 65 and 4 except that the mechanism is in the fully closed position.

Figure 9 is an enlarged view partly in section of the indicating device in a modified form of the invention.

Figure 10 is a bottom plan view of the 70 mechanism shown in Figure 9.

Like reference characters denote like parts in the several figures of the drawing.

In the following descriptions and claims, 75 parts will be identified by specific names for convenience of expression, but they are intended to be as generic in their application to similar parts or the equivalent construction as the art will permit.

Referring to the drawing there is shown in Figure 1, so much of a stringed musical instrument of the type commonly designated as a grand piano as is necessary to an understanding of the invention. As shown, there is provided a casing 10, suitably supported on feet such as 11 and having a lid partly shown 85 at 12 hinged as at 13, it being understood that when in closed position, the hinged cover 12 is coextensive with an opening in the top of the casing 10.

For producing sound within the casing 10, 90 there is provided a plurality of tuned strings, which are tuned to the notes of the musical scale in a conventional manner. For example in the lower or bass part of the scale, such as represented by strings 15, a single string is 95 tuned to each note. In the intermediate portion of the scale the strings 16, 17, are arranged in groups of two strings each, a group being tuned to each note. In the upper portion of the scale the strings 18, 19, 20, are arranged in groups of three strings each, which are tuned to the same note. For striking the

100 string or group of strings tuned to each note there is provided a hammer, such as 21, oper-

- ated through an action 22 by a key 23 in a conventional manner. The key 23 is one of a number of keys of a manual 24 representing the musical scale to be played by the piano.
- 5 The strings are mounted in fixed position relative to the casing 10 being stretched across a suitable metal framework shown diagrammatically as at 25. The hammers 21, the actions 22 and the keys 23 of the manual 24 are 10 mounted upon a movable frame 26 which is slidably mounted within the casing 10, and which is normally held in predetermined position with respect to the casing. The construction is such that when the frame 26 is in the 15 normal position as shown in Figure 1, operation of a key 23 will cause the respective hammer 21 to strike the respective string or group of strings and thus produce sound of predetermined pitch.
- 20 For modulating the sound produced by the piano, the casing 10 is provided with a partition 30, positioned in a plane substantially parallel to and spaced apart from the general plane of the strings and is also provided with 25 an oppositely positioned partition 31. The partition 30 is provided with an opening 32 having a series of modulating reflectors such as 33 for variably controlling the opening. Similarly the partition 31 has an opening 34 30 provided with a series of modulating reflectors such as 35 for variably closing the same. The reflectors 33 are rotatably positioned in the opening 31 of the partition 30. Each reflector 33 is provided on its inner face with a 35 sheet of sound reflecting material such as sheet aluminum, and is provided with an operating arm 36 and the several operating arms of the group are pivotally connected to a movable connecting rod 37. Similarly, each 40 reflector 35 of the lower group is provided with an inner face of sound reflecting material and with an operating arm 38 and the several operating arms of the lower group are pivotally connected to a movable connecting 45 rod 39.

For operatively interconnecting the upper connecting rod 37 and the lower connecting rod 39 there is provided a vertical shaft 40 journaled in suitable bearing plates 41, 42 and 50 extending through a bore 43 in the casing 10. The shaft 40 is connected to the connecting rod 37 at its upper end and to the connecting rod 39 at its lower end in like manner, and a description of one of such connections will 55 suffice for both. Referring to Figure 2, the shaft 40 has affixed thereto an arm 45 to which there is pivotally connected one end of a link 46. The other end of the link 46 is pivotally connected to the respective upper or lower 60 connecting rod as shown in Figures 1 and 2. The shaft 40 is also provided with an operating arm 47 for a purpose which will be subsequently set forth.

For variably operating the reflectors 33, 65 35 there is provided a pedal 50 and an upward-

ly extending shaft 51 operated thereby. The upper end of the shaft 51 engages one arm of a bell crank lever 52 which is pivotally mounted on a bracket or apron 153 secured to the casing 10. Secured to one arm of this bell crank 70 is a spring 53 engaging a cam-shaped stop 54. The stop 54 is secured to a shaft 55 mounted for rotation in bearings 56. The shaft 55 fits snugly in the bearings 56 so that it will remain in any position in which it is left. This 75 shaft is provided with a pointer 57 which may be used for tuning the cam 54 and which indicates the position of this cam on a graduated dial 58. Connected to the other end of the bell crank 52 is a link 60, the other end of 80 which is attached to the arm 47. Secured to the link 60 is one end of a spring 61 the other end of which is fastened to a bracket 62 carried by the frame work of the piano.

In the operation of the form of the invention shown in Figures 1 to 8, the pointer 57 is manually set in any desired position depending upon the amount it is desired to have the tone modulating reflectors open when the pedal is completely depressed. The initial 90 position of the mechanism is shown in Figures 3 and 4 with the rod 51 in its lowest position and the reflectors 35 open.

When it is desired to close the tone modulating reflectors the pedal 50 is depressed, thereby elevating the rod 51 which in turn rotates the bell crank 52 in a counter clockwise direction. This causes the link 60 to be moved to the right which rotates the arm 47 and the shaft 40 in a counter clockwise direction as seen in Figure 2. This rotates the two arms 45 and the two links 46 to the right thus moving the two rods 37 and 39 to the right which causes the reflectors to be closed. This action continues until the spring 53 engages the stop 54 which stops the closing of the reflectors thus leaving them slightly open, the amount of opening depending upon the position of the stop 54 and therefore upon the position of the pointer 57. The mechanism when in this position is shown in Figures 5 and 6. If it is desired to completely close the reflectors, more pressure is applied to the pedal 50, thereby rotating the bell crank 52 against the action of the spring 53 115 until the mechanism is moved into the position shown in Figures 7 and 8, at which time the reflectors will be completely closed.

It is thus seen that in the normal operation of this mechanism, the reflectors are never 120 completely closed, but remain slightly open as shown in Figures 5 and 6. It has been found desirable not to close the reflectors completely, as when they are entirely closed certain upper partials of the notes are suppressed, thereby changing the quality of the music produced. The amount which the reflectors should be left open depends upon a number of facts such as the type of piece being played, the individual piano, the room 125 130

in which it is located, etc., so that this residual opening, as it might be called, may be varied by changing the position of the stop 54 as has already been stated. This can be done by 5 moving the pointer 57 to any desired position before starting to play the piano. If the pianist desires to produce an extra soft effect, however, the pedal may be completely depressed by applying an extra pressure of 10 the foot, thereby entirely closing the reflectors as shown in Figures 7 and 8.

In the modified form of the invention shown in Figures 9 and 10, the spring 53 is eliminated and the shaft 55 is rotatably 15 mounted in two arms 65 and 66 which are rigidly secured to a shaft 67 mounted for rotation in two bearings 68 and 69. Rigidly secured to the shaft 67 is an arm 71 provided at its end with a ball 72 which snugly fits in 20 a recess 73 provided in the frame 26 which carries the piano action and which is normally held to the left by means of the spring 27 as previously described in connection with Figure 1.

25 In the operation of the modified form of the invention shown in Figures 9 and 10, the pointer 57 is set in any desired position as already described in Figures 1 to 8. When the pedal is depressed, the rod 51 will be elevated thus rotating the bell crank 52 and closing the tone modulators as previously described, until the bell crank 52 engages the stop 54. At this time the modulating reflectors will still be slightly open as in the 30 position shown in Figure 6. As the pedal is still further depressed, the stop 54, together with the shaft 55 and the two arms 65 and 66, will be rotated in a clockwise direction, thereby by rotating the arm 71 in a similar direction, 35 thus moving the frame 26 to the right against the action of the spring 27. This will move hammers 21 to the right and bring them out of alignment with at least one of the strings in each group thereby bringing in the soft pedal 40 action of the piano to be thrown on in a well known manner.

45 It is thus seen that the normal operation of this mechanism is the same as that described in connection with Figures 1 to 8. If, however, the pedal is still further depressed, the tone modulators will not only be completely closed, but the soft pedal action of the piano will be thrown on as well, thus producing an additional softening of the tone produced by 50 the piano.

55 The invention upon which this application is based is broader than the specific embodiment shown and described for the purpose of illustrating at least one of the ways in 60 which it may be employed. The scope of the invention is therefore to be understood as not being limited by the present specific description. I intend no limitations other than those imposed by the claims.

What is claimed is:

1. In a musical instrument, the combination with a plurality of strings, means for supporting said strings to permit free vibration thereof, means for vibrating the strings, a casing surrounding the strings, said casing having apertures, a plurality of modulating reflectors positioned in said apertures, each having a compressional wave reflecting surface on its inner face, an operating rod for rotating said reflectors to direct reflected waves in a desired direction with respect to the casing, and an adjustable abutment positioned to engage said rod for controlling the normal extent of movement of said reflectors. 65

2. An instrument for producing damped compressional waves comprising a vibratory element, a casing therefor having apertures, a plurality of sound reflectors rotatably positioned in said apertures forming controllable closures therefor for directing waves produced by said element in a desired direction, and an adjustable stop device for controlling the normal movement of said reflectors. 80

3. In a musical instrument, the combination with a source of sound, of a casing surrounding said source and having an interior reflecting surface to reflect sound, means for varying the amount of sound reflected back to the source from said surface, and an adjustable stop device for effectively limiting 90 the movement of said varying means. 95

4. In a musical instrument, the combination with a source of sound, of a casing surrounding said source, said casing having an aperture for emitting sound, an element positioned in said aperture having on its interior surface a layer of sound reflecting material, means for variably positioning said element to reflect desired proportions of sound back into the casing, and an abutment for effectively limiting the normal movement of said 100 means. 105

5. In a musical instrument, the combination with a plurality of strings, means for supporting said strings to permit free vibration thereof, means for vibrating the strings, a casing surrounding the strings, said casing having apertures, a plurality of modulating reflectors rotatably positioned in said apertures to control the effective opening of said 110 apertures each having a compressional wave reflecting surface on its inner face, means for rotating said reflectors to direct reflected waves in a desired direction with respect to the casing, and adjustable means for effectively preventing the full movement of said 115 rotating means. 120

6. An instrument for producing damped compressional waves comprising a vibratory element, a support for said element a casing having controllable apertures, a plurality of sound reflectors rotatably positioned in said apertures for controlling the effective open- 125

- ing of said apertures, and adjustable means for effectively limiting the minimum opening of said apertures.
7. In a musical instrument, the combination with a source of sound, of a casing surrounding said source and having an interior reflecting surface to reflect sound, said casing having apertures, rotatable reflectors positioned in the apertures, means for rotating 10 said reflectors to control the effective opening of said apertures, and an adjustable stop device for effectively limiting the movement of said means in one direction.
8. In a musical instrument, the combination with a plurality of strings, means for supporting each of said strings for permitting free vibration thereof, and means for vibrating the strings, a casing surrounding the strings, said casing having apertures, a plurality of modulating reflectors positioned in 15 said apertures, each having a compressional wave reflecting surface on its inner face, means for rotating said reflectors to direct reflected waves in a desired direction with respect to the casing, an adjustable but yielding abutment for controlling the normal extent of movement of said means arranged to permit additional movement thereof.
9. In a musical instrument, the combination with a plurality of strings, means for supporting said strings to permit free vibration thereof, means for vibrating the strings, a casing surrounding the strings, said casing having apertures, a plurality of modulating 20 reflectors rotatably positioned in said apertures to control the effective opening of said apertures each having a compressional wave reflecting surface on its inner face, means for rotating said reflectors to direct reflected waves in a desired direction with respect to the casing, adjustable means cooperating with said rotating means for preventing the full closure of said apertures by said reflectors, and an indicating device for indicating the 25 extent of least opening of the apertures.
10. An instrument for producing damped compressional waves comprising a vibratory element, a casing therefor having controllable apertures, a plurality of sound reflectors rotatably positioned in said apertures for controlling the effective opening of said apertures, adjustable means for limiting the minimum opening of said apertures, and an indicator for indicating the extent of minimum opening.
11. In a musical instrument, the combination with a source of sound, of a casing surrounding said source and having an interior reflecting surface to reflect sound, said casing 30 having apertures, rotatable reflectors positioned in the apertures, means for rotating said reflectors to control the effective opening of said apertures, an adjustable stop device for limiting the movement of said rotating means to limit the rotation of said reflectors in one direction, and an indicator for indicating the adjustment of said stop device.
12. In a musical instrument, the combination with a plurality of strings, means for supporting said strings, means for vibrating the strings, a casing surrounding the strings, said casing having apertures, a plurality of modulating reflectors rotatably positioned in said apertures to control the effective opening of said apertures each having a compressional wave reflecting surface on its inner face, means for rotating said reflectors to direct reflected waves in a desired direction with respect to the casing, a spring having relatively strong tension for controlling the extent of movement of the rotating means, and a cam for varying the effectiveness of said spring.
13. An instrument for producing damped compressional waves comprising a vibratory element, a casing therefor having controllable apertures, a plurality of sound reflectors rotatably positioned in said apertures for controlling the effective opening of said apertures, an operating element connected to 40 said reflectors for rotating the same, and a yielding abutment in the path of movement of the operating element for effectively limiting the movement of the reflectors.
14. In a musical instrument, the combination with a source of sound, of a casing surrounding said source and having an interior reflecting surface to reflect sound, said casing having apertures, rotatable reflectors positioned in the apertures, an operating member for rotating said reflectors to control the effective opening of said apertures, a leaf spring positioned in the path of movement of said member, and a cam engaging said spring and arranged to vary the position of the 45 spring relative to said operating member.
15. In a musical instrument, the combination with a piano, of a casing having sound openings, a plurality of normally open centrally pivoted closures for said openings, means controlled entirely at the will of an operator for variably positioning said closures to control the intensity of sustained notes, means interconnecting said controlled means and said closures, and adjustable means for limiting the minimum opening of 50 said closures.
16. In a musical stringed instrument, the combination with a piano, of means for suppressing the sound produced thereby including a casing having a layer of sound insulating material, and having openings for the emission of sound, a plurality of normally open centrally pivoted closures controlled entirely at the will of an operator, a pedal for variably controlling said closures to modify the intensity of sustained notes, means operatively interconnecting said pedal and said closures, adjustable means for limiting the minimum opening of said closures,

and an indicator for indicating the extent of minimum opening.

17. In a musical instrument of the percussive type, the combination with tuned strings, and means for supporting said strings to permit free vibration thereof, of a casing having oppositely disposed apertures,

controllable closures for said apertures, and adjustable means for limiting the extent of movement of said closures.

Signed at New York, in the county of New York and State of New York this seventh day of December, A. D. 1925.

JOHN HAYS HAMMOND, JR.
